(57) **CLAIM**

The ornamental design for a cap and cone combination set, as shown and described.

DESCRIPTION

FIG. 1 is an upper perspective view of a cap and cone combination set in a first configuration.

FIG. 2 is a lower perspective view of the set in the first configuration.

FIG. 3 is a front elevation view of the first configuration, which is substantially symmetrical to a rear elevation view. FIG. 4 is a left elevation view of the first configuration, which is substantially symmetrical to a right elevation view. FIG. 5 is a top plan view of the first configuration.

FIG. 6 is a bottom plan view of the first configuration.

FIG. 7 is a side elevation cross-section view of the first configuration, taken along the line 7-7 in FIG. 5.

FIG. 8 is a perspective side elevation cross-section view of the first configuration, taken along the line 8-8 in FIG. 1. FIG. 9 is an exploded perspective view of the set, presenting a second configuration in which all components of the set are shown; and,

FIG. 10 is a side elevation cross-section view of the set in the second configuration.
